Primary Examiner — Calvin E Vansant*Assistant Examiner* — Giang Hoang Tran(74) *Attorney, Agent, or Firm* — The Compton Law Firm, P.C.; Scott D. Compton(57) **CLAIM**

The ornamental design for a motorcycle protective guard, as shown and described.

DESCRIPTION

FIG. 1 is a top perspective view of a motorcycle protective guard showing my new design;

FIG. 2 is a front side view thereof;

FIG. 3 is a back side view thereof;

FIG. 4 is a left side view thereof;

FIG. 5 is a right side view thereof;

FIG. 6 is a bottom view thereof;

FIG. 7 is a top view thereof; and,

FIG. 8 is a perspective view thereof.

The broken lines of a motorcycle in FIG. 8 are illustrative of environment and form no part of the claimed design.

1 Claim, 6 Drawing Sheets(56)
